WOMAN'S SHOE

Otto F. Stock, Columbus, Ohio, assignor to The Julian & Kokenge Company, Columbus, Ohio, a corporation of Ohio

Application March 14, 1952, Serial No. 18,880

Term of patent 14 years

(Cl. D7—7)

To all whom it may concern:

Be it known that I, Otto F. Stock, a citizen of the United States, residing at Columbus, in the county of Franklin and State of Ohio, have invented a new, original, and ornamental Design for a Woman's Shoe, of which the following is a specification, reference being had to the accompanying drawing, forming a part thereof.

Fig. 1 is a perspective view of a woman's shoe showing my new design;

Fig. 2 is a top plan view;

Fig. 3 is a side elevational view;

Fig. 4 is a similar view looking toward the opposite side of the shoe.

I claim:

The ornamental design for a woman's shoe, substantially as shown.

OTTO F. STOCK.
